UNITED STATES PATENT OFFICE

127,670

DESIGN FOR A LUNCH PAIL

George A. Allen, Denver, Colo.

Application February 27, 1941, Serial No. 99,252

Term of patent 14 years

To all whom it may concern:

Be it known that I, George A. Allen, a citizen of the United States, residing at 1020 West Forty-eighth Avenue, in the city and county of Denver and State of Colorado, have invented a new, original, and ornamental Design for a Lunch Pail, of which the following is a specification reference being had to the accompanying drawing, forming part thereof. The opposite side of the lunch pail is substantially similar to that shown. The characteristic features of my design reside in the depressed portions on the sides of the device.

In the drawing:

I claim:

The ornamental design for a lunch pail, substantially as shown and described.

GEORGE A. ALLEN.
